Primary Examiner — Andrew Kerr(74) *Attorney, Agent, or Firm* — McAndrews Held & Malloy, Ltd.(57) **CLAIM**

The ornamental design for an air fryer adapter, as shown and described.

DESCRIPTION

FIG. 1 is a front perspective view of an air fryer adapter; FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is a bottom perspective view thereof.

The evenly spaced broken lines shown in the drawing figures depict portions of the air fryer adapter that form no part of the claimed design. The dash-dot broken lines shown in the drawing figures define the bounds of the claimed design and form no part thereof.
